(57) **CLAIM**

The ornamental design for an earphone, as shown and described.

DESCRIPTION

FIG. 1 is a rear perspective view of an earphone showing my new design.

FIG. 2 is a front perspective view of the earphone;

FIG. 3 is a front view of the earphone;

FIG. 4 is a rear view of the earphone;

FIG. 5 is a left side view of the earphone;

FIG. 6 is a right side view of the earphone;

FIG. 7 is a top view of the earphone; and,

FIG. 8 is a bottom view of the earphone.

Any shading and cross-hatching are not features of the design but are utilized to illustrate the surface contours of the earphone in the drawings
